UNITED STATES PATENT OFFICE

GEORGE G. McMURTRY, OF ALLEGHENY CITY, PENNSYLVANIA.

PUNCH FOR NUT-MACHINES.

SPECIFICATION forming part of Letters Patent No. 274,957, dated April 3, 1883.

Application filed April 27, 1882. (No model.)

To all whom it may concern:

Be it known that I, GEORGE G. McMURTRY, of Allegheny City, in the county of Allegheny and State of Pennsylvania, have invented a new and useful Improvement in Punches for Nut-Machines; and I do hereby declare the following to be a full, clear, and exact description thereof.

My invention relates to the construction of hollow or tubular punches for punching nuts and like metallic articles; and it consists mainly in perforating the punch at intervals for its entire operative length, whereby its entire operative surface will be cooled or lubricated, as the case may be, and, secondarily, in providing the punch with a separable bit or point, which facilitates the construction and repair of the tubular punch and permits the punch to be altered from a blunt to a pointed punch at will or to suit the work to be done.

To enable others skilled in the art to make and use my invention, I will now describe it by reference to the accompanying drawings, in which—

Figures 1 and 2 are longitudinal sections of my improved punch. Fig. 3 is a view of a modified form. Fig. 4 shows the relative positions of the punch and die-box. Figs. 5 and 6 are forms of caps or end pieces.

Like letters of reference indicate like parts in each.

The punch *a* is hollow, having a central bore, *a'*. It is preferably made of steel-drawn tubing, but may be formed of iron, if desired.

In the latter case I prefer to use refined iron. It is provided with a number of perforations, *a²*, extending through its sides at intervals for its operative length, and the outer end is either solid steel or is fitted with a plug or cap-piece,

b, which may be of any desired form, and is made of steel. In the drawings I have shown two forms, one having a blunt and the other a pointed end, Figs. 5 and 6. The plug is made with a central stem, *b'*, which fits inside of the

bore of the punch, and a flange, *b²*, which extends over the end of the tube *a*, as shown in Fig. 3. This plug constitutes the entering end of the punch. The punch is secured in the nut-machine in the usual way, and has an open

pipe or channel, *c*, to which I attach by any suitable coupling a flexible pipe, *d*. The pipe *d* is connected with a pump or other device

by which a hydraulic pressure may be applied to the interior, *a'*, of the punch. I do not limit myself to the use of the flexible pipe for this purpose, as it may be done by straight tubes having a telescopic joint, which will not interfere with the reciprocation of the punch.

When my improved punch is used for hot punching I force water, by means of a force-pump, elevated tank, or other head, into the cavity *a'*, which, being under pressure, is ejected through the perforations *a²*, and keeps the punch cool both internally and externally and equally on all sides. The water which passes through the perforations *a²* is spread by the movement of the punch in a thin film over the heated iron of the nut-blank and produces better surface on the bore of the nut. It also, striking against the inner surface of the die-box *e* before the nut-blank is forced in or after it is discharged therefrom, washes out all scale and cinder, and thus cleanses the die-box, and so prevents the wearing of the punch and die-box thereby. This is a very important feature when dirty iron is used for making the nuts. By these means I am enabled to run the machine continuously without any stoppage for the cooling of the punch, to prevent the bending of the punch, to reduce the wear of the dies, die-box, and punch, and to make a better nut.

When the punch is used for cold punching I force oil through the perforations *a²*, for the purpose of lubricating it, the oil spreading upon its external surface in the same manner as the water just described. The tubular form of the punch gives it greater strength, and reduces the danger of its being bent and strained under the ordinary pressure to which it is exposed.

The plug *b* is secured in the end of the hollow punch *a* by riveting, or any other way known in the art.

Instead of using the cap-piece, the punch need not be bored entirely through, as in Figs. 1 and 2.

I am aware that for the purposes of cooling and preservation a tubular perforated punch has heretofore been employed, and do not herein claim the same, as the punch was only perforated at or near its extremity to permit the escape of the heated water, &c.; but I am not aware that the perforations have been ex-

tended at intervals along the operative portion of the punch in order to lubricate the same and wash the dirt, scale, &c., from the punch and die-box, and therefore

5 What I claim as my invention, and desire to secure by Letters Patent, is—

1. A hollow or tubular punch having a series of perforations at intervals throughout its operative length, which perforations communicate with the bore of the punch, substantially as and for the purpose specified.

10 2. The combination, with a hollow or tubular punch, of a separable shouldered bit or

punch-point, substantially as and for the purpose specified.

15 3. The combination, with the tubular punch having a series of perforations at intervals throughout its operative length, of a separable shouldered bit or plug-point, substantially as and for the purpose specified.

20 In testimony whereof I have hereunto set my hand this 24th day of April, A. D. 1882.

GEORGE G. McMURTRY.
